UNITED STATES PATENT OFFICE.

WILLIAM THOMAS BIDWELL, OF ATLANTA, GEORGIA.

HEATING-GENERATING PLANT.

1,391,451.

Specification of Letters Patent. Patented Sept. 20, 1921.

Application filed March 15, 1920. Serial No. 365,918.

To all whom it may concern:

Be it known that I, WILLIAM T. BIDWELL, a citizen of the United States, residing at Atlanta, in the county of Fulton and State 5 of Georgia, have invented certain new and useful Improvements in Heat-Generating Plants, of which the following is a specification.

This invention relates to heat generating plants and it is particularly directed to providing a novel smoke consuming apparatus and an improved bridge.

The main object of the present invention is to provide a bridge capable of withstanding or resisting high temperatures, so that the life of the bridge and in consequence the heating plant, will be increased thereby.

A further object of the invention is to locate the steam spraying pipe of the smoke consumer within the heat resisting bridge and to provide said bridge with means for permitting the jets of steam to issue therefrom.

With the foregoing objects outlined and with other objects in view, which will appear as the description proceeds, the invention consists in the novel features herein-after described in detail, illustrated in the accompanying drawings and more particularly pointed out in the appended claims.

Referring to the drawings:

Figure 1 is a perspective view of a steam generating plant having a portion of its wall broken away to exhibit the construction and arrangement of my improved smoke consumer and bridge.

Fig. 2 is a front view of the novel bridge frame and the damper for admitting or controlling the feed of air to the bridge.

Fig. 3 is top plan view of the construction shown in Fig. 2.

Fig. 4 is a top plan view of the bridge, the crown bars of the bridge being removed to exhibit the steam feeding pipe of the smoke consumer.

Fig. 5 is a sectional view taken on the line 5—5 of Fig. 2, but showing the refractory coating of the bridge.

Fig. 6 is a sectional detail of the crown portion of the bridge.

Fig. 7 is a longitudinal sectional view of the bridge taken on line 7—7 of Fig. 5.

Fig. 8 is a fragmentary perspective view of the bridge.

Fig. 9 is a perspective view of one of the crown bars.

Fig. 10 is a similar view of one of the keys used in locking the upper portion of the bridge to its supporting trestle.

Fig. 11 is a perspective view of one of the locking members used in securing the two sides of the bridge proper together.

In the drawings, 1 represents the casing or housing of a steam generating plant in which is located a horizontal tube boiler 2. Located beneath said boiler is a bridge 3 which is spaced away from a vertical baffle 4 that depends from the boiler. The bridge is provided with a supporting bar 5 which supports the rear ends of the grate bars 6.

The bridge proper is supported upon a plurality of trestles 7, there being three trestles in the present instance, but this number may be varied in larger or smaller sized heating plants. Located on the ash pit side of the trestles and secured to the same, is a vertical plate 8 having an air opening 9 controlled by a hinged damper 10, provided with a series of apertures 11 to insure a certain quantity of air being fed to the bridge at all times. The damper is operated by a rod 12 which extends to the front of the casing 1 and has a handle 13 to be engaged by the attendant. The trestles may be arranged at any height desired by placing a brick or other foundation beneath the same.

Mounted on the trestles, are two rectangular, hollow metallic air feeding bridge frames 14 and 15, each of which is provided at its ends with key-ways 16 which receive keys 17 that are slid into similar key-ways provided at the tops of the trestles. These keys act to lock the frames 14 and 15 to the trestle 7.

Each of the frames is provided at its upper edge with a plurality of longitudinal flanges 19 and 20 which act as keys for the crown bars 21 and the front and rear sides of the frames are provided with dovetailed vertical keys 22 which function to reinforce the frames and act as keys for locking the refractory plastic covering 23 to said frames. The ends of the frames are also provided with tapered keys 24, which when the two frame members are placed end to end, receive locking members 25 having dovetailed grooves that receives the keys 24 and locks the two frames together.

As best seen in Fig. 7, a vertical wall 26 extends across the interior of each of the hollow bridge frames and functions to reinforce the frame while the upper end of the mem-

ber 26 is provided with a vertical lug 27 having a curved recess 28 that functions as a seat for the steam supply pipe 29. Each of the crown bars 21 is of arc shape and it is 5 provided at the front portion of its sides with laterally extending arc shaped lugs 30 which, when the crown bars are placed side by side, snugly abut the adjacent lugs 30 of adjacent crown bars. The rear portion of 10 each crown bar has lateral lugs 31 and these lugs are spaced away from the lugs 30, so that the spaces formed thereby, act to provide apertures 32 to permit steam from the pipe 29 to pass to the rear of the bridge.

15 The pipe 29 is provided at its ends with threaded fittings 33 which engage extensions 34 of the pipes 35 and 36. A pipe 37 is connected to the steam dome 38 of the boiler and extends forward of the furnace casing. 20 Its front end is connected to a vertical pipe 39 which passes down the front of the casing and has a control valve 40, and the lower end of the pipe 39 is connected to the front end of a pipe 41, the latter pipe being 25 connected to the lower end of the pipe 35. A pipe 42 is connected to the lower end of the pipe 36 and extends to the front of the casing where it is provided with a drain cock 43.

30 In operation, air passes in beneath the grate 6 and moves rearwardly through the opening 9. There the air is deflected upwardly by means of a forwardly and downwardly inclined refractory plate 44, which 35 is supported by diagonal struts or inclined bars 45 forming part of the trestles. The plate 44 directs the air upwardly through the air passage ways 46 in the bridge frames 14 and 15 and the air passes out of the 40 bridge through the apertures 32.

45 Steam from the boiler passes by means of the pipes 37, 39, 41 and 35 to the pipe 29 and this latter pipe is provided with steam apertures 47, which are arranged in series running in a straight line longitudinally of the pipe 29. The pipe 29 is formed of copper, German silver, Monel metal or similar non-corroding, high heat resisting material and the apertures 47 are of a diameter not 50 more than one-thirty-second of an inch.

55 It has heretofore been proposed to form minute apertures in the steam feeding pipe, but as the pipe was formerly made of corrodable metal easily affected by the highly heated gases and steam, the pipe 29 in corroding caused the apertures to be closed and this affected the efficiency of the smoke consumer. By making the pipe 29 of a material capable of withstanding the highly heated gases and steam without corroding, the apertures 47 will remain open and in consequence the smoke consumer will operate the same at all times.

60 It will be noted that the pipe 29 only rests on the members 27 and is not con-

nected to any part that is fixed. It will also be noted that the pipes 35 and 36 are not directly connected or fixed to the bridge but their lower ends pass through slots 48 in the lower portions of the frames 14 and 15, slots 49 provided in the inner ends of the end keys 17, and slots 50 provided in the upper portions of the end trestle 7. This construction will permit the pipes 35 and 36 to expand or contract without damaging 75 said pipes.

The steam from the pipe 29 may be directed nearly vertical through the apertures 32 or nearly horizontal through said apertures, by simply turning the fittings 33. 80

85 The baffle 4, as before stated, is arranged a distance from the crown of the bridge to provide a throat 51 which will be bounded on the front by the bridge, on the rear by the lower end of the baffle and on the sides by the inner surfaces of the side walls of the casing. The lower end of the baffle preferably extends below the peak of the bridge, in order that the gases passing over 90 from the fire box, will be directed into close proximity to the air and steam issuing from the bridge and this construction will cause the gases to travel in an S-shaped path. The baffle is preferably of refractory material and it is preferably provided with air passage ways 52 which permit air from the exterior of the plant to cool said baffle.

95 In making up the bridge a foundation is first prepared a suitable distance back from the front of the casing, to receive the trestles 100 7, the frames 14 and 15 and crown bars 21 are subsequently placed in position, and then plastic refractory material is placed on the bridge. In the front of the bridge, this refractory material extends from the grate 105 bars 6 to a point at the top of the crown bars, while the refractory material on the rear of the bridge extends upwardly only to the lower walls of the apertures 32 and this plastic material acts to protect the bridge and prevent excessive heat from reaching the interior of the same.

110 The refractory baffle 4 and throat 51 while shown as vertically arranged, may be arranged at any suitable angle relatively to the bridge, the object in any case being to form a throat for the passage of the gases and to provide a hot baffle to receive the jets of steam issuing from the apertures 32. The baffle is supported by the side walls of the 115 furnace.

120 The rear ends of the grate bars 6 are shown as supported by the bridge but it will be understood that other means for supporting the grate bars may be used without departing from the invention.

125 In certain types of boilers the trestles may be substituted by other supporting means and I do not wish to confine the invention to supporting the bridge by trestles alone. 130

While I have shown and described the steam pipe 29 as supported by special fittings within the bridge and the pipes 37, 39 and 41, as extending forwardly and down the front of the boiler, it is obvious that steam may be fed from the dome 38 through a pipe extending down the side of the furnace wall and through the wall at this side, to the bridge.

10 The pipe 29 is formed of suitable metal which is non-corrosive under heat, so as to maintain the apertures 47 unclosed at all times.

I am aware that various changes and modifications may be made in the construction shown, without departing from the spirit of the invention as set forth in the following claims.

What I claim and desire to secure by Letters Patent is:—

1. A furnace bridge comprising a plurality of parallel trestles spaced apart and each provided with a forwardly and downwardly inclined bar, an apertured plate arranged across the front ends of the trestles and the aperture of said plate having its bottom edge arranged in alinement with the lower ends of said inclined bars, a damper for regulating air passing through said aperture, a forwardly and downwardly inclined air deflecting plate supported by the inclined bars and having its lower edge arranged adjacent to the lower edge of said aperture, a hollow bridge body supported by said trestles and having an apertured crown, said body being arranged directly above said inclined plate so that air passing through the aperture of the apertured plate is directed upwardly through the apertures in the crown of the bridge body.

2. A furnace bridge including supporting means provided with upwardly opening dove-tailed channels, a hollow bridge body carried by the supporting means and having downwardly opening dove-tailed channels, and double dove-tailed blocks fitted in said channels and functioning to lock the bridge body to the supporting means while permitting expansion and contraction of the

bridge body relative to the supporting means.

3. A furnace bridge including a body formed of hollow rectangular body members arranged end to end, dove-tailed keys arranged on the outer sides of the body members, locking members having dove-tailed grooves which engage a plurality of the dove-tailed keys of the body members for locking said body members together, and masonry refractory material molded onto said keys and said locking members and covering the opposite sides of the bridge body.

4. A furnace bridge including supporting means provided with vertical slots, a hollow bridge body carried by the supporting means and provided with vertical slots arranged in alinement with the other slots, an apertured crown for the bridge body, said bridge body being provided with vertical partitions having grooved upper edges, an apertured steam pipe resting in said grooves and unsecured to the bridge body, a pipe for supplying steam to the apertured pipe extending through certain of said slots and secured to one end of the apertured pipe, and a drain pipe secured to the other end of the apertured pipe and passing through the other slots in said supporting means and bridge body.

5. A furnace bridge comprising supporting means having an apertured plate, an inclined air deflecting plate carried by the supporting means and having its lower edge abutting the lower edge of the aperture of the apertured plate, a hollow metallic bridge body carried by the supporting means and arranged directly above the inclined plate, a removable metallic crown fitted to the upper edge of said bridge body and provided with rearwardly directed apertures, a covering of masonry refractory material molded on to the opposite sides of said bridge body and covering substantially the entire front half of the crown, and a steam pipe arranged within the crown for directing steam through the apertures in the crown.

WILLIAM THOMAS BIDWELL.
